US0D1075293S

(12) United States Design Patent (10) Patent No.: US D1,075,293 S
(45) Date of Patent: * May 20, 2025

(54) BIFOLD WALLET

(71) Applicant: Thread Wallets LLC, Provo, UT (US)

(72) Inventors: Colby S. Bauer, Provo, UT (US);
Dillon M. Boyes, Vineyard, UT (US)

(73) Assignee: Thread Wallets LLC, Provo, UT (US)

() Term: 15 Years

(21) Appl. No.: 29/865,260

(22) Filed: Jul. 15, 2022

Related U.S. Application Data

(63) Continuation of application No. 16/983,884, filed on Aug. 3, 2020, now abandoned.

(51) LOC (15) Cl. 03-01

(52) U.S. Cl.

USPC D3/247

(57) CLAIM

The ornamental design for a bifold wallet, as shown and described.

DESCRIPTION

FIG. 1 is a bottom, right, facing perspective view of a first embodiment showing an open configuration of our new design for a bifold wallet;

FIG. 2 is top, plan view thereof;

FIG. 3 is bottom, plan view thereof;

FIG. 4 is an elevated, facing view thereof;

FIG. 5 is an elevated, rear view thereof;

FIG. 6 is an elevated left, side view thereof;

FIG. 7 is an elevated right, side view thereof;

FIG. 8 is a bottom, right, facing perspective view of a second embodiment showing a closed configuration of our new design for a bifold wallet;

FIG. 9 is top, plan view thereof;

FIG. 10 is bottom, plan view thereof;

FIG. 11 is an elevated, facing view thereof;

FIG. 12 is an elevated, rear view thereof;

FIG. 13 is an elevated left, side view thereof; and,

FIG. 14 is an elevated right, side view thereof.

Spaced apart rectangular shapes along the edges of the design represent stitching that forms part of the claimed design. Dashed lines represent unclaimed subject matter that forms no part of the claimed design.

1 Claim, 7 Drawing Sheets
